UNITED STATES PATENT OFFICE.

JUDSON MOORE, OF BAINBRIDGE, GEORGIA.

DESIGN FOR A SHOE-DISPLAY RACK.

47,797.

Specification for Design.

Patented Sept. 7, 1915.

Application filed June 8, 1915. Serial No. 32,978. Term of patent 14 years.

To all whom it may concern:

Be it known that I, JUDSON MOORE, a citizen of the United States, residing at Bainbridge, in the county of Decatur and State of Georgia, have invented a new, original, and ornamental Design for a Shoe-Display Rack, as shown in the accompanying drawing and described in the following specification.

In the drawings: Figure 1 is a view of the improved display rack in front elevation. Fig. 2 is a view of the improved display rack in edge elevation.

The shoe display rack which forms the subject matter of this design comprises a base 10 of double quarter round as shown, with uprights 11 secured to such base and joined at the top by an arch structure 12.

Intermediate the base and the top of the uprights 11 cross-bars 13 are employed carrying struts 14 with plates 15 secured thereon at an inclination to the uprights 11. At their lower or forward ends the plates 15 are rounded as indicated at 16, while a cleat or strip 17 is secured transversely across the plate removed at a greater distance from the forward rounded end than from the opposite end.

I claim:

The ornamental design for shoe display rack as shown and described.

JUDSON MOORE.

Witnesses:

GEO. H. FIELDS,
M. A. ANDERSON.
